UNITED STATES PATENT OFFICE.

RUFUS D. PETTIT, OF BALDWINSVILLE, NEW YORK.

IMPROVEMENT IN ROTARY STEAM-ENGINES.

Specification forming part of Letters Patent No. 72,537, dated December 24, 1867.

To all whom it may concern:

Be it known that I, RUFUS D. PETTIT, of Baldwinsville, in the county of Onondaga and State of New York, have invented a new and useful Improvement in Rotary Engine; and I do hereby declare that the following is a full, clear and exact description thereof, which will enable those skilled in the art to make and use the same, reference being had to the accompanying drawings, forming part of this specification, in which—

Figure 1 is a vertical longitudinal section, taken in the line *y y*, Fig. 2, and Fig. 2 is a vertical cross-section, taken in the line *x x*, Fig. 1.

Similar letters of reference indicate corresponding parts.

In the accompanying drawings, A is the cylinder or shell; B is the central disk or wheel, which is secured to the shaft *b*, and carries the pistons.

The shell A has two abutments, E E, so that the steam-space or working-chamber is divided into two parts, D D.

F F are the pistons, which slide radially in suitable slots in the central disk B, and have each a head, *f*, on their inner end, which works in a chamber, G, into which steam is admitted for throwing the pistons out. On the rear side of each piston is a small steam-passage, H, leading through the disk B to the chamber G, and on the opposite side of each piston is a similar steam-passage, *h*.

The passages H are to admit steam to the inner ends of the pistons while the engine is going ahead, and the opposite passages *h* perform the same duty when the engine is reversed. Each set of passages H *h* has a valve, I, which is suspended by a wrist or head, *i*, in such manner as to swing freely, and close one of the passages, H or *h*, while the steam for throwing out the piston is entering the opposite passage.

J J are metallic packings for the abutments, and they are made adjustable by set-screws *j j*.

There are two exhausts, K K, for going ahead, and two exhausts, *k k*, for reversing the engine. There are also two induction-pipes, L L, for going ahead, and another set of inductions, *l l*, for reversing the motion of the engine.

M M' are packing-rings, which are made sufficiently wide to cover the entire sides of the working-chambers D D, so that any wear on the sides of the pistons F can be taken up by means of set-screws *m* and the packing-rings M M'. The packing-rings M M' also lap onto the outer edge of the center disk B, (as shown at B D, Fig. 2,) so that all rubbing parts in the steam-space are kept tight by these rings, except the outer ends of the pistons, which are pressed out by steam in the chambers, G, so that a tight joint is obtained at their outer ends; and as their ends become worn they move farther out, and thus all wear on the ends of the pistons is taken up.

The abutments E have longitudinal slits or channels, *n*, in their inclines, which allow the steam in front of an approaching piston (after it has passed the exhaust) to escape to the rear side of the piston.

Its operation is as follows: When the engine is to be run ahead, the exhausts *k k* are closed, and also the inductions *l l*, and the exhausts and inductions K K L L are brought into use; but for running the engine backward, this order of the parts is reversed. Steam enters the two working-chambers D D simultaneously, from the inductions L L, and the engine moves forward. As a piston, F, reaches an abutment, it is pushed into the center disk B by the incline of the abutment, as usual; but after passing the abutment, steam from the induction L acts down the passage H, and throws the valve I over, so as to close the opposite passage, *h*, and at the same time throws out the piston F, so that a steady pressure is obtained in the chamber G, for holding the piston out against the outer shell of the cylinder during the remainder of the stroke. The channels *n*, in the approaches to the abutments, prevent steam from choking the advance of a piston after it has passed its exhaust, and also, where double-inclined abutments are used, they prevent any vacuum forming behind a piston when leaving an abutment, and before it has passed the induction. The packing-rings M M' are so broad as to cover the entire sides of the working-chambers, and represent adjustable side walls for said chambers.

By these means I obtain an engine which, owing to its being balanced, and to the easy adjustment of all wearing parts, has less wear and friction and greater endurance than ordinarily.

Having thus described my invention, what I claim as new, and desire to secure by Letters Patent, is—

The combination of the cylinder A, exhausts K K k k, inductions L L l l, abutments E E, disk B, and sliding pistons F, with actuating

steam-chambers and conduits G H h, valves I, and packing-rings M M', all constructed, arranged, and operating substantially as and for the purpose specified.

The above specification of my invention signed by me this 17th day of October, 1867.

RUFUS D. PIETTIT.
